UNITED STATES PATENT OFFICE

JOHN JOS. CH. SMITH, OF PHILADELPHIA, PENNSYLVANIA.

IMPROVEMENT IN MACHINES FOR CUTTING TYPE.

Specification forming part of Letters Patent No. 31,333, dated February 5, 1861.

To all whom it may concern:

Be it known that I, JOHN JOSEPH CHARLES SMITH, of Philadelphia, in the county of Philadelphia and State of Pennsylvania, have invented a new and Improved Machine for Cutting Type; and I do hereby declare that the following is a full, clear, and exact description of the same, reference being had to the accompanying drawings, forming a part of this specification, in which—

Figure 1 represents a plan or top view of this invention. Fig. 2 is a transverse vertical section of the same, the line xx , Fig. 1, indicating the plane of section.

Similar letters of reference in both views indicate corresponding parts.

The object of this invention is a simple and efficient machine for cutting types from a solid block, the surface of which is formed into types at such distances apart that a saw may be passed through between them without injury to the types. Such blocks, which may be formed by the process described in Letters Patent granted to me September 20, 1859, and reissued April 10, 1860, or in any other convenient manner, I propose to cut up first into strips containing one type in width and a large number of types in length, in such a position that the required nicks or notches can be made into all the types contained in one of the strips by one operation, and after the strips have thus been prepared I propose to cut them up into single types. This operation is one of great nicety, since it is necessary to cut the types perfectly even and of uniform thickness.

My invention consists in the arrangement of a reciprocating cutter, in combination with an automatically-moving gripping-jaw, and with an adjustable gage, in such a manner that the gage can be set for types of different thickness, while the jaw adjusts itself to the varying width or size of different types, and that by each stroke of the cutter one type is cut off and deposited in a receptacle that may be placed under the cutter.

To enable those skilled in the art to make and use my invention, I will proceed to describe its construction and operation with reference to the drawings.

On the platform A, and near to one of its sides, is a channel, B, which serves to feed the strips of type to the cutter C. The channel B is formed by the stationary strip a and a bar, b , which is adjustable to different sizes

of type. The cutter is secured in a reciprocating head, D, which moves up and down in the dovetailed guides c , motion being imparted to the same by means of a pitman, d , from the driving-shaft E, or in any other convenient manner. The cutter may be firmly secured to the cutter-head, as shown in the drawings, and in this case it is set in an inclined position, the upper teeth being made to overhang the lower ones to such a degree that one stroke of the head D is sufficient to pass the cutter through the entire width of the strip. Instead of securing the cutter firmly to the head, a rotary cutter might be used, which would produce the same effect.

The thickness of the type is determined by a gage, F, which is adjustable by means of a set-screw, e , and a sliding jaw, G, grips the end of the strip of types while the cutting is performed. This jaw is connected by a link, f , to a lever, H, which is fulcrated on a pivot, g , in a standard, h , under the platform A, and to which an intermittent oscillating motion is imparted by a cam, I. A spring, i , forces the lower end of the lever H up against the surface of the cam, and this cam is so shaped that the jaw G is allowed to recede at regular intervals, thereby releasing the types after they have been cut, so that they drop down into a receptacle, which may be placed under the platform. This cam may be attached to the driving-shaft E, as shown in the drawings, or it may be connected to the cutter-head, or arranged in any other convenient manner, so as to produce the desired result.

By this machine a very large number of types can be cut off in a very short time, and after the machine has once been set to a certain size type it requires no extra attention of the operator until it is desired to change the machine for another size type, and it is very easy and simple to adjust the same to any type which it may be desired to cut.

Having thus fully described my invention, what I claim as new, and desire to secure by Letters Patent, is—

The arrangement of the adjustable gage F and automatic jaw G, in combination with the reciprocating cutter C, constructed and operating substantially in the manner and for the purpose specified.

JOHN JOS. CH. SMITH.
